(No Model.)

S. B. JONES.
BARREL TRUNK.

No. 432,138.

Patented July 15, 1890.

UNITED STATES PATENT OFFICE.

SOPHIA B. JONES, OF ATLANTA, GEORGIA.

BARREL-TRUNK.

SPECIFICATION forming part of Letters Patent No. 432,138, dated July 15, 1890.

Application filed January 18, 1890. Serial No. 337,287. (No model.)

To all whom it may concern:

Be it known that I, SOPHIA B. JONES, a citizen of the United States, residing at Atlanta, in the county of Fulton and State of Georgia, 5 have invented a new and useful Barrel-Trunk, of which the following is a specification.

This invention relates to barrel-trunks, or that class of trunks which are constructed in the shape of a barrel for the purpose of enabling them to be conveniently handled without danger of breakage; and it consists in certain improvements in the details of construction of the same, which will be hereinafter fully described, and particularly pointed out 15 in the claims.

In the drawings hereto annexed, Figure 1 is a perspective view of my improved barrel-trunk, showing the same with the lid or cover open. Fig. 2 is a longitudinal vertical sectional view 20 of the same. Fig. 3 is a vertical transverse sectional view of the same, taken on the line *x x* of Fig. 2. Fig. 4 is a detail view of one of the detachable feet of my improved trunk. Fig. 5 is a sectional detail view taken on line 25 *y y* in Fig. 2.

Like numerals of reference indicate like parts in all the figures.

The body of my improved trunk, which is designated by 1, is composed of staves 2 2, 30 suitably connected by hoops 3, and joined to the heads 4 in the usual manner.

The heads are provided with handles 5, which may be constructed of leather straps, which are bolted or riveted to metallic straps 35 6, which extend diametrically across the heads 4 and have their ends 7 bent around the edges of the said heads and into the chines of the staves. By this construction the heads are braced and strengthened and the handles are 40 prevented from coming loose by ordinary handling of the trunk.

The trunk is provided with a hinged lid or cover 9, which is composed of sections or portions of several of the staves, which are suitably 45 connected by means of metallic binding straps or braces 10. A strip 10^a is also secured at the front edge of the lid. A lock 11 of any suitable construction may be employed for the purpose of retaining the cover in a closed position. One of the ends of the cover is partitioned off from the body of the trunk at the point where one side of the cover terminates 50

by means of semicircular lids 12 12, both of which are hinged to a horizontal partition 13. One or both of the sub-compartments thus formed may be subdivided by vertical partitions 14 into smaller compartments of convenient size and shape. Sliding latches or fastenings of any suitable description may be employed to retain the hinged lids 12 in a closed 60 position.

15 designates a tray, which is adapted to be mounted upon cleats 16, secured longitudinally at the front and rear sides of the hinged cover. This tray, which is of suitable shape 65 to fit the bulge of the trunk, may be of any suitable size and may be subdivided into smaller compartments, when desired.

The under side of the barrel-body of the trunk is provided with recesses 17, which are 70 four in number, located at the corners of a rectangle and provided with cross-bars 18, which may be formed by staples driven into the staves of the trunk. 20 designates one of the feet, which is composed of a strip of metal 75 bent or doubled upon itself so as to form a brace 21, adapted to bear against the outside of the trunk-body and having its upper end bent so as to form a spring-catch 22, adapted to be inserted under the staple or cross-bar 80 18 and to rest in the recess 17, the bent portion or spring-catch 22 serving to prevent the leg from dropping out when the trunk is lifted. It will be seen that by this construction the feet may be readily placed in position, when 85 desired, to keep the trunk-body from rolling, while at the same time, when the trunk is to be transported, the said feet may be readily detached and packed into the trunk.

The operation of my invention and its advantages will be readily understood from the foregoing description, taken in connection with the drawings hereto annexed. When the trunk is in use, the feet may be readily placed in position, and the trunk will thus be sustained in an upright position. When the trunk is to be transported, the feet may be quickly detached and packed within the trunk, thereby avoiding the danger of their being broken in transit. 90 95 100

Having thus described my invention, what I claim is—

1. In a barrel-trunk, the combination, with the body having recesses provided with cross-

bars, of the detachable feet having their ends bent to form braces abutting against the body of the trunk, said feet being provided at their upper ends with bent portions adapted to be inserted into the said recesses over the cross-bars, substantially as set forth.

2. In a barrel-trunk, the combination, with the trunk-body having recesses provided with cross-bars, as described, of the spring-feet having braces to abut against the body of the trunk and bent ends adapted to be inserted into the recesses over the cross-bars and to be retained in said recesses by the spring-catches formed by the bent ends engaging the cross-bars, substantially as set forth.

3. In a barrel-trunk, the combination, with the body having the hinged lid or cover, of the semicircular lids 12, hinged to a horizontal partition in one end of the trunk, and the tray supported removably upon longitudinal 20 cleats adjacent to the front and rear sides of the cover, substantially as set forth.

In testimony that I claim the foregoing as my own I have hereto affixed my signature in presence of two witnesses.

SOPHIA B. JONES.
